COLLAPSIBLE TOILET SEAT FOR BEDS
Charles Russell Carroll, Glace Bay,
Nova Scotia, Canada
Application September 23, 1948, Serial No. 50,769
5 Claims. (Cl. 5—90)

1 This invention relates to toilet seats for beds, for the use of bed-ridden patients in hospitals or elsewhere, and the main object of the invention is to provide in relatively simple, compact and efficient form an equipment of this kind which may be attached to the side of any conventional bed, and so constructed and supported that the seat thereof may be either moved and adjusted to convenient position above the bed for the use of the patient, or may be removed from such position and projected underneath the bed and out of the way when not required for use.

Another object of the invention is to provide in a unit of the kind referred to, a metallic basal slat for anchoring at its ends medially to the side rails of a conventional bed, at the under margins thereof, a slide-bracket or shoe slidably mounted on the basal slat, a hanger lug rigidly depended from the slide-bracket, a reach rod firmly anchored at its inner end to the lower end of the hanger lug and extended horizontally outward in parallelism with the said basal slat, the arrangement being such that with the slide-bracket and hanger lug positioned medially upon the basal slat, the outer free end of the reach rod will project out laterally and substantially below a side rail of the bed, a toilet seat supporting post bored through at its lower end and thereby journaled upon the outwardly projected free end of the reach rod, whereby said post may be turned up vertically alongside the bed or may be turned down horizontally and then pushed out of the way underneath the bed, means for stopping and locking the post at either its vertical or horizontal position, a toilet seat supporting collar, or seat elevator collar, slidably mounted upon the said post, a seat supporting bar firmly and laterally anchored at its outer end to the said collar with its free end arranged to project horizontally inward over the bed when the supporting post is turned up vertically and the reach-rod is pushed inwardly, a toilet seat mounted at the inner end of the seat supporting bar and means for sliding the said seat supporting collar towards either end of the seat supporting post, whereby the connected toilet seat may be raised or lowered as positioned over the bed.

Still another object of the invention is to provide in combination with a bed having side rails, a toilet seat unit of the kind described, the same comprising a cross member anchored at its ends medially to the under margins of the side rails of the bed, a reach-member slidably connected at its inner end with the said cross-member, and adapted to be drawn out laterally below one of

2 the side rails, a post mounted on the outer end of the reach-member and arranged to turn up vertically at the side rail or to turn down horizontally alongside the side rail, a collar slidably mounted on the post, a seat supporting bar extended inward from the said collar, a toilet seat supported at the inner end of the seat supporting arm, and means for slidably positioning the said collar at any selected point upon the said post.

10 With the stated objects in view, together with such additional objects and advantages as may appear from the specification, attention is directed to the accompanying drawing as embodying a preferred form of the invention, and wherein:

Figure 1 is a perspective view of the toilet seat unit as mounted upon a conventional form of bed, the toilet seat being shown as positioned over the bed, in position for use.

20 Figure 2 is a cross-section on the line 2—2 of Figure 1.

Figure 3 is a view similar to that of Figure 2, showing however the toilet seat unit or assembly as drawn outwardly at the side of the bed, preliminary to turning the unit down alongside the bed in position for pushing same underneath the bed.

30 Figure 4 is a view similar to that of Figure 3, showing however the toilet seat unit as turned down and pushed underneath the bed.

Figure 5 is a vertical section on the line 5—5 of Figure 3.

Figure 6 is a vertical section on the line 6—6 of Figure 3.

35 Figure 7 is a vertical section on the line 7—7 of Figure 4.

The toilet seat unit comprising the subject matter of this invention, is designed for mounting upon a side rail R of a conventional form of bed B, and for this purpose a metallic basal slat 5 is anchored at its ends medially to the side rails R and thus extended transversely across the under side of the bed. A slide-bracket or shoe 6 is apertured through as at 6a (Figure 7) conformally with a cross-sectional form of the slat 5, and is thereby slidably mounted upon said slat. A pair of spaced hanger lugs 1 are rigidly depended from the bracket or shoe 6, these lugs being bored through in alignment at their lower ends, as at 1a, for receiving the inner end of a reach rod or arm 8, which is then firmly anchored in place by means of pins 9 passed through the lugs and through the inserted end of the rod 8. The reach rod 8 is additionally braced and supported by an angle rod 8a connected at its ends,

as at 8b, to the slide shoe 6 and the outer end of the rod 8 (Figures 2 and 3).

A seat supporting post 10 is provided and is enclosed at its lower end in a ringed socket or cage 11, the same comprising a pair of spaced collars or rings 11a, 11b, connected by a neck piece 11c, as shown in Figure 2 of the drawing. The ring or collar 11b is pinned to the post 10 as indicated at 11d (Figures 5 and 6). This post and its encircling lower ring 11a is bored through as at 12, as means for journaling the post upon the outer end of the reach-rod 8. Before this is done however, a stop-bracket 13 (Figure 5), formed with an arcuate ninety degree slot 13a at its outer lateral margin, and with a concentric, bored hub 13b at its inner corner, is keyed upon the outer end of the reach rod 8 in a spaced relation from the extremity thereof, by inserting the end of the rod through the hub 13b and then passing a pin 14 through the hub and rod. The post 10 is then journaled upon the extended end of the reach-rod 8 outwardly of the stop bracket 13, and is operatively secured in place by boring and tapping the end of the rod and seating a headed set screw 14a into this threaded bore. The post 10 is additionally bored through as at 15, in spaced and parallel relation to the bore 12, and in exact alignment with the arcuate slot 13a of the bracket 13. A headed lock pin 16 is then passed through the slot 13a and through the bore 15 of the post 10, the outer end of the lock-pin being threaded to engage a lock-nut 16a. Thus by turning up the nut 16a, the bracket 13 is drawn up against the neck piece 11c of the socket 11, for frictionally locking the post 10 to any adjusted position, such as to the vertical position as required in the use of this toilet seat assembly.

A cap 17 is pinned as at 17a atop the post 10, and bearing lugs 18 are rigidly extended, in alignment, from the cap 17 and from the ring or collar 11b of the socket 11. These bearing lugs are formed with sockets 18a for receiving the reduced and journaled ends 19a of a worm 19 (Figure 6). A driven pinion-bevel-gear 20 is keyed, as at 20a, Figure 3, upon the lower end of the worm 19, above the lower bearing lug 18. An integrally formed collar-bracket or yoke 21 is provided, and is mounted by passing the post 10 through the collar 21a thereof (Figure 6) and keying it in place, as at 21b. The bracket portion 21c of this yoke is open, as at 21d, and in the assembling of the elements, the worm 19 is passed through this open portion of the yoke. The outer end of the bracket portion 21c is bored through, as at 21e, and a stub drive shaft 22 is journaled through this bore. A bevel drive gear 23 is keyed upon the inner extended end of the shaft 22, as at 23a (Figure 4) and placed in mesh with the driven gear 20, and a crank-wheel 24 is keyed as at 24a upon the outer extended end of the shaft 22. A handle 24b is extended from the wheel 24. A toilet seat supporting collar or seat elevator collar 25 is slidably mounted upon the post 10, and a lug 25a is rigidly anchored to this collar, as shown at 25b, this lug being bored and tapped as at 25c for threadedly engaging the worm 19, this arrangement being thus effectuated in assembling these elements of the unit.

A short and sturdy seat supporting bar or arm 26 (Figures 2, 3, 4) is rigidly joined to and extended horizontally from the inner side of the elevator collar 25, in position to extend inwardly over the bed in the use and operation of the unit. Any desirable form of toilet seat 27 may be rigidly mounted at the inner end of the bar or

arm 26. As here shown, however, a flat, U-shaped, metallic seat-plate 27a (Figure 2) is welded or otherwise anchored to the inner end of the arm 26 and thus arranged for horizontal extension inwardly over the bed when in use. Metallic guide strips 27b are anchored atop the legs of the seat-plate in parallel relation, and these guide-strips are extended rearwardly, as shown at 27c, and are notched at their upper sides, as at 27d (Figure 4). The strips 27b are marginally undercut, as at 27e (Figure 2), and thus adapted to slidably and lockingly engage a U-shaped wooden seat 27f which is formed at its under side with marginally undercut guide-grooves 27g for receiving and holding the complementally formed guide-strips 27b. The cover 27h is formed in simulation of a regular chair back (for the ease and comfort of the patient), and is hinged at 27k to the rear margin of the wooden seat 27f. A U-shaped back brace 27m is pivotally attached to the back of the cover 27h by passing the inturned extremities of the free ends of the back brace through screw eyes 27n seated in the said cover. The right portion of the brace 27m thus falls angularly rearward, in position for locating in any selected aligned pair of the notches 27d of the strips 27b, for the purpose of angularly adjusting the cover 27h to best function as a chair back for the patient.

In connection with the use of this apparatus, any desirable form of bed pan P may be employed and positioned upon the mattress M, as indicated in dotted lines in Figures 2 and 3.

In operation, the entire unit is turned down and pushed underneath the bed, as represented in Figure 4. When the toilet seat is desired for use, the operator grasps the post 10 and pulls it and attached seat 27 outwardly of the side rail R of the bed and so that the seat clears the side rail of the bed. The post and seat are then turned up vertically, as shown in Figure 3 and are pushed inwardly over the bed, and the seat is raised and adjusted as desired. The bed-pan P is then positioned under the seat, after which the patient is assisted onto the seat. After use, the described operations are reversed and the apparatus collapsed and pushed under the bed, out of the way.

From the foregoing description, it is thought that the construction and operation of the invention will be fully understood. And while I have here shown and described a preferred form of the unit and specific structural features thereof, these features may be changed, modified or replaced as desired, within the scope of the claims.

I claim:

1. In a unit of the kind referred to, a metallic basal slat for anchoring at its ends medially to the side rails of a conventional bed, at the under margins thereof, a slide-bracket or shoe slidably mounted on the basal slat, a hanger lug rigidly depended from the slide-bracket, a reach-rod firmly anchored at its inner end to the lower end of the hanger lug and extended horizontally outward in parallelism with the said basal slat, the arrangement being such that, with the slide bracket and hanger lug positioned medially upon the basal slat, the outer free end of the reach rod may project out laterally and substantially below a side rail of the bed, a toilet seat supporting post bored through at its lower end and thereby journaled upon the outwardly projected free end of the reach rod, whereby said post may be turned up vertically alongside the bed or may be turned

down horizontally and then pushed out of the way underneath the bed, means for stopping and locking the post at either its vertical or horizontal position, a toilet seat supporting collar or seat elevator collar, slidably mounted upon the said post, a seat supporting bar firmly and laterally anchored at its outer end to the said collar with its free end arranged to project horizontally inward over the bed when the supporting post is turned up vertically and the reach rod is pushed inwardly, a toilet seat mounted at the inner end of the seat supporting bar and means for sliding the said seat supporting collar towards either end of the seat supporting post, whereby the connected toilet seat may be raised or lowered as positioned over the bed.

2. For mounting upon a rectangular form of bed including side boards, end boards and supporting legs, an elongated basal slat for anchoring at its ends medially to the lower margins of the side rails of the bed and extending transversely and horizontally thereunder, a slide bracket slidably mounted on the basal slat, a reach-rod rigidly joined at its inner end to the slide bracket and arranged to be drawn out horizontally and laterally below a side rail of the bed, a seat supporting post journaled on the outer end of said reach rod and arranged for turning up vertically at the side of the bed or for turning down horizontally there along, a seat supporting collar slidably mounted on the seat supporting post, a seat supporting arm rigidly joined at one end to the said seat supporting collar and arranged to be turned inwardly over the bed, a toilet seat mounted at the inner end of the seat supporting arm, and means for slidably positioning and locking said seat supporting collar at any position on the post.

3. In a toilet seat unit according to claim 2, releasable means for locking the said seat supporting post into either its vertical or its horizontal position relative to the bed upon which it is mounted.

4. In a toilet seat unit according to claim 3, the said means for locking the seat supporting post to vertical or horizontal position comprising an arcuately slotted bracket fixedly keyed upon the outer end of the reach rod, and a headed lock-pin passed through the slot of the bracket and freely through the seat supporting post, and a lock-nut threadedly seated upon the outer extended end of the lock-pin for drawing the bracket up against the post for locking these elements against movement.

5. In a toilet seat unit according to claim 2, the said means for slidably positioning and locking the seat supporting collar on its post comprising a pair of bearing lugs fixedly supported upon the post, in spaced and longitudinal alignment thereon, a worm journaled vertically between said lugs, a bracket supported laterally from the post, a crank shaft journaled on the bracket, gear connections operable by the crank shaft and operably meshing with the said worm, and a lug rigidly attached at its inner end to the seat supporting collar, the outer end of said lug being bored and tapped for threadedly engaging and passing the said worm therethrough, whereby the said seat supporting collar, seat supporting arm and toilet seat thereon may be raised or lowered by rotation of the said crank shaft.

CHARLES RUSSELL CARROLL.
